UNITED STATES PATENT OFFICE.

RUPERT ARTHUR SHIELDS AND CHARLES FREDERICK BRAYBROOKE, OF LUTON,
ENGLAND.

CARBURETER.

1,317,047.

Specification of Letters Patent. Patented Sept. 23, 1919.

Application filed June 11, 1918. Serial No. 239,380.

To all whom it may concern:

Be it known that we, RUPERT ARTHUR SHIELDS and CHARLES FREDERICK BRAYBROOKE, subjects of the King of Great Britain, both residing at 67 Highbury road, Luton, Beds, England, have invented new and useful Improvements in Carbureters, of which the following is a specification.

This invention relates to improvements in carbureters.

According to this invention the fuel is supplied through a needle valve held upon its seat by a spring and having a stem upon the surface of which is a spiral groove. The stem is surrounded by a jacket and the needle valve together with the stem is actuated by a Bowden wire. The lower end of the jacket and the needle valve, which is preferably tapered, extends into a fuel reservoir, while the upper end of the stem extends into the induction pipe of the engine. In the induction pipe is a spring controlled valve which is opened to allow of the passage of air by the suction of the engine.

The accompanying drawing shows a carbureter made in accordance with this invention and is a section of the same.

A is a tapering needle valve having a stem C upon the surface of which is a spiral groove D. Where the needle valve joins the stem C a head for the valve is provided by tapering the lower end of the stem. When the valve is closed, said head rests on a seat B. As before stated the needle itself is tapered, the taper being very slight, but when the needle is fully inserted it may close the connection between the fuel chamber and the spiral groove in the valve stem, but the construction is also such that the communication between the fuel chamber and the spiral groove may be closed by the head of the needle. At the top of the stem C is a spring E which constantly tends to press the needle valve upon its seat, and F is a Bowden wire connected to the stem C and by which the needle valve is lifted. The stem C is surrounded by a jacket G which together with the needle valve extends into a fuel reservoir H. The upper end of the stem C extends into the induction pipe J of the engine and K is an air entrance pipe in which is a valve L held closed against a stop M by a spring N. When the needle valve A is lifted off its seat by means of the Bowden wire the fuel flows past the

tapering needle valve up the spiral groove D where it meets the incoming air which is drawn past the valve L by the suction of the engine.

What we claim is:

1. In a carbureter the combination of a needle valve, a seat for the same, a spring adapted to press the needle valve upon its seat, a stem upon the needle valve, a spiral groove upon the stem, a jacket surrounding the stem and means for actuating the needle valve.

2. In a carbureter the combination of a needle valve, a seat for the same, a spring adapted to press the needle valve upon its seat, a stem upon the needle valve, a spiral groove upon the stem, a jacket surrounding the stem and a Bowden wire for actuating the needle valve.

3. In a carbureter the combination of a needle valve extending into a fuel reservoir, a seat for the same, a spring adapted to press the needle valve upon its seat, a stem upon the needle valve, a spiral groove upon the stem, a jacket surrounding the stem, a jacket surrounding the stem and means for actuating the needle valve.

4. In a carbureter, the combination of a needle valve, a seat for the same, a spring adapted to press the needle valve upon its seat, a stem upon the needle valve, a spiral groove upon the stem, a jacket surrounding the stem, said stem extending into the induction pipe, and means for actuating the needle valve.

5. In a carbureter, the combination of a needle valve, a seat for the same, a spring adapted to press the needle valve upon its seat, a stem upon the needle valve, a spiral groove upon the stem, a jacket surrounding the stem, said stem extending into the induction pipe, and a Bowden wire for actuating the needle valve.

6. In a carbureter the combination of a tapered needle valve, a seat for the same, a spring adapted to press the needle valve upon its seat, a stem upon the needle valve, a spiral groove upon the stem, a jacket surrounding the stem and means for actuating the needle valve.

7. In a carbureter, the combination of a tapered needle valve extending into a fuel reservoir, a seat for the same, a spring adapted to press the needle valve upon its seat, a stem upon the needle valve, a spiral groove upon the stem, a jacket surrounding the stem and a jacket surrounding

the stem and means for actuating the needle valve.

8. In a carbureter, the combination of a tapered needle valve, a seat for the same, a spring adapted to press the needle valve upon its seat, a stem upon the needle valve, a spiral groove upon the stem, a jacket surrounding the stem, said stem extending into

the induction pipe, and means for actuating the needle valve.

10 In testimony that we claim the foregoing as our invention we have signed our names this 18th day of May, 1918.

RUPERT ARTHUR SHIELDS.
CHARLES FREDERICK BRAYBROOKE,

Copies of this patent may be obtained for five cents each, by addressing the "Commissioner of Patents, Washington, D. C."
